UNITED STATES PATENT OFFICE.

CHARLES C. MENGEI, OF LOUISVILLE, KENTUCKY, ASSIGNOR TO MENGEI BOX COMPANY,
OF LOUISVILLE, KENTUCKY, A CORPORATION OF NEW JERSEY.

KNOCKDOWN BOX.

No. 927,265.

Specification of Letters Patent.

Patented July 6, 1909.

Application filed August 31, 1908. Serial No. 450,995.

To all whom it may concern:

Be it known that I, CHARLES C. MENGEI, a citizen of the United States, residing at Louisville, in the county of Jefferson and 5 State of Kentucky, have invented certain new and useful Improvements in Knock-down Boxes, of which the following is a specification.

This invention pertains to "knock down" 10 boxes, crates or receptacles, and the novelty resides primarily in the construction of strengthening cleats employed at or near the ends of the boards forming the top, bottom, and sides of the receptacle.

15 The present invention is one of a series, closely related, all of which are designed to permit the utilization of veneer board or compound lumber, which combines strength and lightness, and effects a great diminution 20 in the aggregate amount of lumber required for the production of a given number of boxes or receptacles; hence tends to the conservation of the timber supply. To give such boxes, crates, and receptacles the required 25 site strength and rigidity, and particularly to protect them against crushing strains, splitting, etc., it is found desirable to apply cleats to the boards forming the top, bottom and sides; and it is further found important to construct 30 these cleats in such manner that they shall properly align themselves and maintain their alignment when the top, bottom and side boards are brought to "assembled" position, ready for use as a receptacle. In all 35 other respects the box may be of any desired construction of the general "knock down" type,—that is to say, the manner of connecting and securing the boards one to another, the character of the boards, and other details 40 may vary as desired, the present invention being concerned mainly with the construction of the cleats above noted.

The invention is illustrated in the accompanying drawings, in which:

45 Figure 1 is a perspective view of the body of the box in a partially folded condition, indicating its capacity to be laid out in one common plane, or folded into rectangular or box form at will; Fig. 2, a perspective view showing the same completely folded, and also showing portions of the heads or ends, the remainder being broken away better to show the body of the box; and Fig. 3, a perspective view of the miter-joint, mortise 50 and tenon of two adjoining cleat sections.

A, B, C, D, indicate four boards, which will preferably, though not necessarily, be of compound lumber or veneer board, placed edge to edge, and connected by any suitable flexible connection. In the drawings I have 55 shown a series of wires, E, stapled to the outer faces of the boards, said wires serving the double purpose of connecting the boards and of binding and strengthening the structure when assembled or folded into box form. 60

The proximate edges of the boards are chamfered or beveled at an angle of 45°, where a rectangular box is to be formed, as here indicated, but of course the structure may have any desired number of sides from 65 three upward, and the angle of the bevel will vary accordingly. F indicates a cleat, of which there are two, secured in any convenient way to the inner face of each of the boards A, B, C, D, one at or near each end. 70

Both ends of each cleat are beveled or chamfered to the same angle as the edges of the board to which the cleat is secured, the bevel of the cleat and of the board being in common plane and forming one a continuation 75 of the other.

The cleats are preferably formed of three-ply veneer board or compound lumber, though this is not essential, a solid cleat being to a certain extent the equivalent of a 80 compound one, though not possessing all of its advantages. Each cleat is provided with a mortise a at one end, and with a tongue or tenon b at the other end. These can be made with peculiar facility in the case of 85 compound lumber by employing a middle layer of a length less than that of the cleat by an amount equal to its width, both ends of said middle layer being left of rectangular or unbeveled form and one end being placed 90 flush with the extreme end of the cleat, thus leaving open or unoccupied a middle space at the opposite end. The rectangular portion which projects beyond the bevel at one end forms the tenon, and the open or unoccupied 95 space at the opposite end constitutes the mortise. No cutting, fitting or matching is required, provided the parts be cut in the first instance to standard measurements. Obviously, however, the mortise and tenon 100 can be formed by cutting away the superfluous wood after the cleat is built up. The cleats are, as before noted, secured to the boards A, B, C, D, preferably flush with the 105 ends thereof, though they may be set in from 110

the ends somewhat if desired. In such case the distance must be uniform, in order that the cleats, and their mortises and tenons, may aline perfectly.

5. In practice it is found convenient to secure both the wires E and the cleats F to the boards by staples straddling the wires, and passing through the boards and into the cleats, though this is not essential. Any 10 convenient fastenings may be employed. The end boards G are merely pieces of proper dimensions, preferably of compound or veneer lumber, placed within the box and against the cleats before the cover section is 15 folded down, and the box completed by twisting together or otherwise securing the free ends of the wires. They may, if desired, be additionally secured by light cleats c, parallel with but slightly removed from the 20 cleats F, or in any other convenient manner. The box being thus constructed is laid out flat for storage or shipment in empty condition, the end boards being laid flat thereon between the cleats F. When required for 25 use, the end pieces are set against the cleats of a side or bottom board, and the boards A, B, C, are folded about the end pieces, the top or cover board being left open to permit the filling of the receptacle, after which it too is 30 folded down to complete the structure, and the wires are twisted together. The structure is cheap, light, strong, and convenient, and the interlocking tenons and mortises preclude any end play or shifting of the boards, 35 which is a result of considerable importance in a structure of this character.

The mitering of the edges of the boards and of the cleats insures close, tight joints rendering the receptacle rigid, and practically 40 dust and water-tight, thus effectually protecting the contents against injury though transported in dusty or rainy weather. In some cases the end boards may be omitted, as where only a protecting covering is desired, and the object shipped is of such character as to remain in the receptacle without 45 the use of heads or end boards.

Having thus described my invention, what I claim is:

50 1. A knock-down box or receptacle consisting of a series of boards arranged edge to edge, said proximate edges being chamfered; cleats secured to the faces of said boards, one at each end, beveled to the same angle as the 55 edges of the boards and provided with inter-

locking tenons and mortises; and flexible connections uniting the boards.

2. A knock-down box or receptacle comprising a series of boards flexibly connected edge to edge and having their proximate 60 edges beveled or chamfered; and a series of cleats secured to said boards, one near each end of each board, each cleat having a mortise a at one end and a tenon b at the other end, and beveled or chamfered each side of 65 the mortise and tenon, substantially as set forth.

3. A knock-down box consisting of a series of boards flexibly connected at their edges and having their proximate edges chamfered, 70 and a series of cleats secured to the boards, one near each end of each board, said cleats being formed of three-ply veneer board or compound lumber, the middle layer having rectangular ends and the outer layers chamfered or beveled at the same angle as the 75 boards, and the middle layer being flush with one extremity of the outer layers but stopping short of the other extremity, whereby there is produced a mortise a at one end and 80 a tenon b at the other end of each cleat.

4. The herein described knock-down box, comprising boards A, B, C, D, beveled along their longitudinal edges; wires E secured to and flexibly connecting said boards; cleats F 85 secured to said boards and having their ends beveled at like angle with the boards and provided respectively with mortises a and tenons b; and heads or end boards G, all substantially as described and shown. 90

5. A knock-down box or receptacle comprising a series of boards flexibly connected edge to edge; and a series of cleats secured to said boards, each cleat comprising three layers of veneer secured facewise, the outer 95 layers being beveled at both ends and the intermediate layer having rectangular ends, one end extending to the extreme end of the cleat where its protruding portion forms a tenon, and the other end stopping short of 100 the extremity of the cleat to leave an open space or mortise.

In testimony whereof I have signed my name to this specification in the presence of two subscribing witnesses.

CHARLES C. MENGEI.
